REVOLVING CHRISTMAS TREE STAND

Anthony N. Masone, Waterbury, Conn.

Application June 19, 1947, Serial No. 755,652

1 Claim. (Cl. 248—45)

1

This invention relates to Christmas tree stands, and more particularly to a revolving stand of the above nature having connections for supplying electric current to electrical apparatus.

One object of this invention is to provide a device of the above nature having outer bearings whereby the Christmas tree will be supported with increased stability.

Another object is to provide a device of the above nature wherein a thrust bearing is provided directly beneath the tree to carry the weight thereof, as well as the outer bearings which impart stability to the tree.

Another object is to provide a device of the above nature which includes an outer electric outlet revolving with the stand, and safe and reliable connections between said outlet through an interior fixed hub to a stationary source of current.

A further object is to provide a device of the above nature which will be simple in construction, inexpensive to manufacture, easy to install and manipulate, compact, ornamental in appearance, and very efficient and durable in use.

With these and other objects in view, there has been illustrated on the accompanying drawing, one form in which the invention may conveniently be embodied in practice.

In the drawings,

Fig. 1 represents a plan view of the revolving Christmas tree stand with a portion broken away to show the interior mechanism.

Fig. 2 is a cross sectional view, on a vertical plane, substantially through the center of the stand, and showing the butt of a tree supported thereby.

Fig. 3 is a view partly in vertical section, taken substantially on the line 3—3 of Fig. 1, showing the central thrust bearing, the fixed hub, and electric contact features.

Fig. 4 is a wiring diagram showing the electrical circuits of the revolving stand.

Referring now to the drawings in which like reference numerals denote corresponding parts throughout the several views, the numeral 10 indicates generally a revolving stand supporting the butt 11 of an upright Christmas tree. The stand 10 is supported on a pair of intersecting cross bars 12 having downturned offset ends forming feet 13 adapted to rest on a floor or other horizontal surface.

In order to support the weight of the tree, a cylindrical hub 14 is mounted centrally on the cross bars 12 and is secured thereto by angle clips 15 and screws 16 (Figs. 2 and 3). The upper end of the hub 14 is formed with an inner circular recess 17, within which is fitted an annular ball bearing 18, including angular outer and inner raceways 19 and 20, and balls 21.

The ball bearing 18 supports a concentric

2

flanged washer 22, comprising a cylindrical portion 23 formed with a circular recess 24 on the outer portion of its lower end to receive the inner raceway 20 of the bearing 18, whereby the washer 22 is rotatable about a vertical axis.

A depending cylindrical shield 25 is disposed exteriorly of the washer 22 and overlaps the hub 14 in closely spaced relation in order to afford protection for the bearing parts. The flanged washer 22 and the cylindrical shield 25 are secured to the underside of a horizontal circular revolving plate 26 by any desired means, as for example, by welding. A central upstanding spike 27 threaded into the upper side of the plate 26, is adapted to receive the butt 11 of the Christmas tree, whereby said tree will be located for rotation with the plate 26 directly above the bearing 18, and the supporting hub 14.

While the ball bearing 18 and the other parts described above will furnish a solid support for the Christmas tree, stabilizing means for holding the tree firmly erect is provided comprising a circular track 28 (Figs. 1 and 2) having the cross sectional form of an upwardly-facing channel. The track 28 is secured to the cross bars 12 concentrically with the hub 14 by rivets 29.

The under side of the revolving plate 26 is provided with three spaced rollers 30 rotatably attached thereto by a plurality of angle brackets 31 secured by rivets 32. The rollers 30 are adapted to travel around the circular track 28 as the stand rotates, and thereby furnish a stable support for the revolving plate 26.

The Christmas tree is held erect upon the plate 26 by a collar 33 embracing the butt 11 and supported at a distance above the spike 27 by a plurality of downwardly diverging arms 34, which have their upper ends riveted to said collar 33 and their lower ends held in clips 35 riveted to the upper surface of the revolving plate 26. It will be seen that the arms 34 will carry any lateral forces directly from the butt 11 downwardly through the plate 26, the angle brackets 31, and the rollers 30 to the track 28, which is solidly supported on the floor by the cross bars 12. Thus, there will be strong resistance to any tendency on the part of the tree to overturn.

In order to rotate the plate 26 and the tree thereon, a motor 36 is mounted on one of the cross bars 12 between the hub 14, and the track 28, as by a strap clamp 36a.

The motor 36 has a pulley 37 which rotates in a vertical plane and drives a belt 37a which engages a large driven horizontal pulley 38 secured against the under face of the revolving plate 26 concentrically with the flanged washer 22.

In order to guide the belt 37a into the proper planes of operation, a pair of guide pulleys 39 are provided to support said belt so as to be tangential to the pulleys 37, 38. The guide pulleys

39 are mounted in a pair of angular arms 40 comprised in an upright bracket 41 (Figs. 1 and 2), said bracket being mounted upon one of the cross bars 12, adjacent the drive pulley 37.

Electric current is supplied to the motor 36 through a cord 42 having a terminal plug 43 adapted to be connected to any suitable source of power. In order to furnish current to a plug 44 and a cord 45 leading to the Christmas tree lights or other electrical apparatus (not shown), on the tree or stand 10, an electric outlet or receptacle 46 is mounted in an aperture 47 on a peripheral concealing skirt 48 formed on the circular revolving plate 26, whereby the plug 44 and the cord 45 will rotate freely with the stand to avoid any danger of twisting or kinking said cord.

The receptacle 46 receives electric current from the cord 42 through a pair of conductors 63, 58, comprised in a branch 49 of said cord which leads into the interior of the hub 14 through an aperture 50.

As a provision for mounting the electrical conductors, the hub 14 has an inner flange 51 spaced from the top of said hub, and secured therein by a cylindrical portion 52 preferably welded to the hub. The flange 51 fits into a circular recess 53 at the lower end of an insulating block 54, in order to rigidly support said block.

A vertical pin 55 concentric with the bearing 18 passes through the block 54, and has an upper contact head 56 and a lower nut 57 which holds the conductor 58 of the cord branch 49. A vertical eccentric pin 59 also passes through the block 54 and has an upper head 60 secured to a slip ring 61 which is concentric with said contact 56, and a lower nut 62 which secures the other conductor 63 of the cord branch 49. An insulating washer 64 secured upon the eccentric pin 59 will retain the block 54 in place, and also insure that the conductor 63 is insulated from the flange 51.

The cylindrical portion 23 of the flanged washer 22 contains an upper insulating block 65 retained therein by an inturned rim 66 of the cylindrical portion 23. A concentric stud 61 and an eccentric stud 68 are threaded into the lower surface of the block 65, and have, respectively, a U-shaped spring contact 69 and a roller contact 70 which will maintain electric connection with the contact head 56 and the slip ring 61, respectively, throughout rotation of the Christmas tree stand.

Conductors 71 and 72 of a cord 73 are passed through aligned apertures in the shield 25, the washer 22, and the block 65, and are secured to the studs 67 and 68, respectively.

In order to avoid interference with the internal mechanism of the stand, the cord 73 is passed upwardly through an aperture 14 of the plate 26 inwardly of the driven pulley 38, and downwardly through an outer aperture 75 into the interior of the stand 10, where it is connected to the receptacle 46.

A concave cover 76 secured to the plate 26 by screws 77 protects and conceals the cord 73 above the plate 26.

Operation

The improved revolving Christmas tree stand may be supplied to the user fully assembled, and it will only be necessary to place it in a desired location upon a horizontal surface, whereupon the butt 11 of the Christmas tree will be inserted through the collar 33 and forced upon the spike 21. The plug 43 will then be inserted into any convenient electrical outlet.

During the operation of decorating the Christmas tree, it may be desired to provide lights or other electrical apparatus to enhance the artistic appearance. This apparatus is conventionally supplied with the cord 45 and the plug 44 shown in Fig. 2 of the drawing, and said plug will be then inserted into the receptacle 46, whereupon a continuous supply of electric current will be assured during rotation of the tree.

One advantage of the revolving Christmas tree stand described herein is that no fire hazard will exist from the electrical connections of the stand. It will be understood that the electric cord 42 will be held stationary, and will not be disturbed by any of the revolving parts. The cord 45 of the electrical apparatus upon the stand will rotate with the revolving plate 26 and the objects supported thereon, and consequently, cannot become snagged by objects revolving with the stand.

The contacts within the hub 14 of the stand are fully insulated and protected from dirt and against short-circuiting or interference with exterior objects.

A further advantage of this invention is that the weight of the Christmas tree is directly supported by a thrust bearing located under the butt of the tree, and the outwardly spaced bearings 30 together with the inclined arms 34 will firmly and reliably brace the tree against overturning even though the tree is in rotation.

While there has been disclosed in this specification one form in which the invention may be embodied, it is to be understood that this form is shown for the purpose of illustration only, and that the invention is not to be limited to the specific disclosure and may be modified and embodied in various other forms without departing from its spirit. In short, the invention includes all the modifications and embodiments coming within the scope of the following claim.

Having thus fully described the invention, what is claimed as new, and for which it is desired to secure Letters Patent, is:

In a revolving Christmas tree stand, a stationary supporting base, a revolving plate, an annular bearing supporting said plate on said base, means for supporting a Christmas tree in erect position on said plate, insulated electric conductor means extending from the stationary supporting base through said annular bearing to said revolving plate, and adapted to conduct current to electrical apparatus upon said plate, said conductor means including relatively movable contacts mounted within said annular bearing for maintaining the continuity of the conductor means during continued revolution of the revolving plate, a receptacle, and means mounting said receptacle on said plate.

ANTHONY N. MASONE.
